(57) **CLAIM**

The ornamental design for a USB cable, as shown and described.

DESCRIPTION

FIG. 1 is a top view of the USB cable in an open configuration, the bottom being a mirror image thereof.

FIG. 2 is a right side view the USB cable in an open configuration, the left being a mirror image thereof.

FIG. 3 is a front view of the USB cable in an open configuration.

FIG. 4 is a rear view of the USB cable in an open configuration.

FIG. 5 is a top, front, right perspective of the USB cable in an open configuration.

FIG. 6 is a right side view of the USB cable in a closed configuration, the left being a mirror image thereof; and, FIG. 7 is a top, front, right perspective of the USB cable in a closed configuration.

In the drawings, the broken lines are for the purpose of illustrating portions of the USB cable that form no part of the claimed design.
